UNITED STATES PATENT OFFICE.

JOHN SCALABRINO, OF NEW YORK, N. Y., ASSIGNOR TO WOLF T. GOLDSMITH, OF NEWARK, NEW JERSEY.

DESIGN FOR A HAND-BAG FRAME.

53,643.

Specification for Design.

Patented July 22, 1919.

Application filed May 17, 1919. Serial No. 297,973. Term of patent 3½ years.

To all whom it may concern:

Be it known that I, JOHN SCALABRINO, a citizen of the United States, and a resident of the city of New York, borough of Manhattan, in the county and State of New York, have invented a new, original, and ornamental Design for Hand-Bag Frames, of which the following is a specification.

Reference is to be had to the accompanying drawing in which the figure is a view in elevation of a hand bag frame, showing my new design.

I claim—

The ornamental design for a hand bag frame, as shown.

JOHN SCALABRINO.
